FEEDING CHAIN FOR WOODWORKING MACHINES

Filed April 19, 1932

INVENTOR

George Bendix

UNITED STATES PATENT OFFICE

GEORGE BENDIX, OF KOENIGSBERG, GERMANY

FEEDING CHAIN FOR WOODWORKING MACHINES

Application filed April 19, 1932, Serial No. 606,182, and in Germany July 1, 1930.

My invention relates to feeding chains for wood working machines and specially to the improved construction of feeding bolts lying in the chain links.

5 The object of my invention is to create stop portions which protrude beyond the surface of the chain in case they are not pressed down by stocks, so that they can be used to grasp behind the stock which requires to be pushed 10 forward or adjust the front corner of the stock newly fitted.

There are further advantages which will be clearly understood after comprehending the nature of the invention.

15 With reference to these and other objects the invention consists in certain newly constructed details, combinations and adjustments as described hereinafter and pointed out in the appended claim.

20 As the drawing only shows one embodiment of the invention, it is evident that in adjustment of other relations and requirements numerous alterations referring to shape, proportion and small specialties of construction can be executed without departing from 25 the spirit of the invention.

In the drawing:

Fig. 1 is a partial elevational view of the feeding mechanism. Fig. 2 is a transverse 30 section seen from line 2—2 of Figure 1. Fig. 3 is a plan view of that part of the mechanism shown in Figure 1. Fig. 4 is a longitudinal section of a portion of the feeding chain. Fig. 5 is a plan view of this portion 35 of the feeding chain. Fig. 6 is a transverse section seen from line 6—6 of Figure 4. Fig. 7 is a view of one of the feeding bolts.

40 Corresponding parts are denoted in the following description and in the different views of the drawing by the same numbers.

With reference to the drawing, 1 denotes the single links of the endless feeding chain, which in their ends grip each other and have axle borings held together by bolts 2 which 45 are conducted through the axle borings.

Each chain link 1 has a guiding hole 3 vertical to the surface of the chain. In this hole 3 is a cylindrical feeding bolt 4 thus, 50 that this bolt can be moved axially. The bolt 4 has a slit 5 in which rests the free end of a

spiral spring 6 protruding beyond bolt 4 whilst the other end is turned round the next bolt 2. The spring 6 is bent thus, that it has the tendency to push the bolt 4 towards the surface of the chain link until the free end of the spring 6 touches the chain link and thus limits the utmost position of bolt 4. But if bolt 4 is in reverse position, for example in that portion of the chain which hangs down and is not in use, as shown in Figure 1, a pin 55 7 which goes through the bolt 4 comes in application. This pin 7 is placed thus, that it prevents bolt 4 from dropping out of the spring 6 as well as out of the guiding hole 3.

Feeding bolt 4 has at its end a stop portion 8 formed by flattening of feeding bolt 4, which flattenings are placed in the moving and reverse direction of the chain. The stop portion 8 is intended to push against stock 9 and either to push forward the stock or to be a stop for the stock which is pushed from behind. In the latter case the stock is pushed by the workman until caught from behind by feeding bolts. Those of the feeding bolts 4 which are not in use for the time being are pressed by the weights of the stock by overcoming the small resistance of spring 6 below the surface of chain links 1 as shown in Figure 4 on the left feeding bolt.

In the example of construction shown the chain is placed on the chain bed 10 as it can be provided on both sides of the feeding mechanism of the wood working machine. This chain bed 10 has on its surface prismatical guiding slides, on which the chain links slide by their correspondingly formed guiding grooves 11. The movement of the chain is caused by the chain wheel 12 formed in octagon shape thus, that the length of each side corresponds to the distance between any two joining bolts 2 of the chain. Moreover the chain is guided by the guiding wheels 13, 14, 15, which are also angular and of which 15 is movable by means of axially pushable 95 arm 16 in using a screwing arrangement 17 in order to stretch the chain.

I wish it to be understood that I do not desire to be limited to the exact details of construction shown and described, for ob-

vious modifications will occur to a person skilled in the art.

What I claim is:

- In a feeding chain of the kind described,
5 chain links with guiding holes running vertically to the surface of the chain links, feeding bolts axially slidabie in the said guiding holes, having a stop portion normally protruding beyond the surface of the chain link
10 and intended to push the stock lying on the chain, springs attached to the joining bolts of the chain links and holding the stop portions of the feeding bolts pushed outward if the latter are not axially pressed down by
15 a stock lying on the surface of the chain links and covering the mouths of the guiding holes for the feeding bolts, means adapted to limit the advance of the feeding bolts and to prevent the dropping out of the latter
20 when chain links are in inverted position.

In testimony whereof I affix my signature.

GEORGE BENDIX.
